TUBE COATING APPARATUS

James F. Barnes, Van Nuys, and Herman I. Silversher, Los Angeles, Calif., assignors to Foil Process Corporation, Van Nuys, Calif., a corporation of California

Application March 23, 1956, Serial No. 573,565

5 Claims. (Cl. 93—80)

This invention relates to a tube coating apparatus, and more specifically to an apparatus for applying lubricative or protective materials upon the inner surfaces of tubes during their fabrication by tube winding machines.

In order to reduce friction during the spiral winding of paper or other materials upon the mandrels of tube winding machines, efforts have been made to apply lubricants directly upon the strips or webs as they are being spirally wound. For this purpose, the hollow mandrels of such machines have been connected to lubricant reservoirs so that lubricant may pass through the mandrels and be applied directly upon the webs through mandrel slots or openings. Similar methods have been employed to coat the inner surfaces of the spirally wound tubes with protective or sealing materials.

In practice, however, it is found that such coating techniques are generally unsatisfactory. For one thing, the direct flow of fluid upon the webs often produces uneven or irregular coatings upon the inner surfaces of the tubes. If porous or absorbent materials are being spirally wound upon the machine, the fluid may penetrate certain portions of the webs passing directly over the ports while other portions of those webs receive insufficient amounts of the coating fluid. In some instances, the localized penetration may become excessive, thereby weakening the tubes or otherwise impairing the quality of the finished product. Further, since a certain amount of fluid invariably remains within the hollow mandrels even after the reservoir passages have been closed, temporary shutdown or speed reduction of the machines may result in saturation of portions of the webs and may prevent or interfere with the continuation of winding operations.

Therefore, one of the main objects of the present invention is to provide coating means for tube winding machines which overcome the aforementioned defects and disadvantages of present structures. Another object is to provide means for insuring an even distribution of protective or lubricative materials upon the inner surfaces of tubes as they are being formed upon the mandrels of tube winding machines. A further object is to provide fluid retaining means for wiping the inner surfaces of tubes with fluid coating materials while those tubes are being spirally wound, the means also being adapted to retain fluid in order to prevent excessive fluid distribution when winding speeds are reduced.

Other objects will appear from the specification and drawings, in which—

Figure 1 is a broken perspective view of a tube winding machine equipped with the tube coating structure of the present invention; Figure 2 is a broken transverse cross sectional view taken along line 2—2 of Figure 1; Figure 3 is an enlarged broken cross sectional view showing a structural variation of the form of the invention represented in Figures 1 and 2; Figure 4 is a broken perspective view showing structural details of a second variation of the first form of the invention; and Figure 5 is a broken longitudinal cross sectional view representing another form of the invention.

Referring to the drawings, Figure 1 shows a stationary mandrel 10 rigidly supported at one end by standard 11 of a tube winding machine. On opposite sides of cylindrical mandrel 10 are vertical cylinders or rollers 12 which are journaled in frames 13 provided by the winding machine. An endless tube winding belt 14 is entrained about the rollers, and has a portion thereof looped or twisted about mandrel 10. Since the structure so far described is entirely conventional and well known in the art, a more detailed presentation is believed unnecessary herein.

As shown in Figure 1, mandrel 10 is provided with a plurality of longitudinal grooves or channels 15 along the outer periphery thereof. While three channels are shown in Figure 2, it will be understood that a larger or smaller number may be provided depending upon the size of the channels, the dimensions of the mandrel, and the character of the material to be wound thereon. From Figure 2 it will be seen that each of the channels are in communication with a vertical passage 16 in the solid end portion of the mandrel adjacent standard 11, by means of separate radial passages 17. Passage 16 may be threaded to receive a fluid flow conduit 18 extending between the mandrel and a suitable tank or reservoir 19. Conduit 18 is preferably provided with a valve 20 for regulating the flow of fluid from reservoir 19. While a gravity system for feeding fluid to the mandrel is shown in the drawing, it will be understood that mechanical means such as a pump may be used to create fluid pressure.

Wicks composed of a resilient absorbent material (such as felt) are carried within the channels 15 of mandrel 10. As illustrated in Figures 1 and 2, wicks 21 are elongated and have a generally rectangular cross section. Each of the wicks 21 extends the length of a channel 15 and is snugly held within its respective channel so that its outermost surface is co-extensive with the periphery of the mandrel. Preferably, the bottom of each channel has reduced lateral dimensions to provide a fluid flow passage 22 in communication with one of the radial passages 17. Consequently, when valve 20 is opened, absorbent wicks 21 will become saturated with tube coating fluid supplied from the reservoir and flowing along passages 22.

Figure 3 illustrates a variation of the wick and wick-supporting structure shown in Figures 1 and 2. In Figure 3, the wicks 23 each have a pair of longitudinal recesses 24 adjacent the bottom wall of each of the grooves 15. The arcuate recesses 24 provide relatively large surface areas for fluid penetration into the wicks and, in combination with the lower walls of grooves 15, provide longitudinal flow passages for the distribution of fluid to the wicks. The fluid then passes from the wicks to the wick-contacting inner surface of tube 25, as will be explained shortly.

Figure 4 shows another structural modification of the wick and wick support. The elongated channel insert member 26 has a generally rectangular cross section, and is adapted to be received within a longitudinal channel provided by the mandrel of a tube winding machine. Screws (not shown) or other suitable securing means may be used to mount the channel member within the mandrel recess. A plurality of wick elements 27 are carried by each of the hollow channel members, and project through rectangular openings 28 along the outer surfaces 29 of those members. When the channel members are properly mounted within the mandrel recesses, the outer surfaces 29 of the members and the exposed surfaces of the cube-like wicks are co-extensive with the periphery of mandrel 10. It will be noted that members 26 have longitudinally extending chambers 30 of substantially greater lateral dimension than wicks 27. As a result, fluid from reser-

voir 19 may flow through chambers or passages 30 and circulate about the wick elements.

When the tube winding machine is in operation, endless belt 14 is rotated by power-driven rollers 12. Webbing 25 is fed upon mandrel 10 in the conventional manner and is spirally wound upon the stationary mandrel to form a tube. The fluid saturated wicks provided by the mandrel wipe against the inner surface of the rotating tube and evenly distribute a thin film of fluid upon that surface. The particular fluid used for any given tube winding operation depends upon the purpose which the fluid is to serve, and the nature of the material being wound upon the mandrel. For instance, if the strips or webs being wound upon the mandrel are formed of paper or other porous material, a wax such as liquid paraffin may be used. Such waxes act not only as release agents for reducing friction between the mandrel and the tube being formed thereon, but also serve as a waterproof coating material for the inner surface of the tube.

Since the wicks run longitudinally along the mandrel, the rotating tube being formed thereon is continuously wiped by the fluid retaining wicks. If, for any reason, the speed of the winding operation must be reduced, the absorbent wicks will tend to retain fluid and prevent the distribution of excess amounts of fluid upon the inner surface of the tube.

Where the material being wound upon the machine is metal foil, it is evident that the metal-to-metal contact results in considerable frictional resistance between the tube and mandrel. Since the metal foil is relatively non-absorbent, an oil such as a light hydrocarbon oil may provide a suitable anti-friction or release agent. As the spirally wound foil tube twists upon the mandrel, the longitudinally extending wicks distribute an even film of oil over the entire inner surface of the tube.

Figure 5 represents another embodiment of the present invention which differs from the form shown in Figures 1 and 2 only in the manner by which fluid is conveyed to the wicks. Hollow mandrel 31 is identical to the mandrel already described, and has a plurality of longitudinal grooves 32 along its periphery which are adapted to tightly receive wicks 33. Fluid reservoir conduit 34 is threaded received by the mandrel, and communicates with a vertical bore 35 extending from the wall of mandrel 31 into an inner plug 36 securely mounted within horizontal mandrel bore 37. A short flow passage 38 communicates with both the vertical bore 35 and the larger horizontal bore 37 so that fluid may flow from the reservoir into the hollow mandrel.

At the opposite unsupported end of the mandrel is a plug or cap 39 which may be welded or otherwise secured to the mandrel, and which tightly seals mandrel bore 37. A plurality of radial flow passages 40 extend between the central bore 37 of the mandrel and wick elements 33. Consequently, when horizontal bore 37 is filled with coating fluid during operation of the tube winding machine, the fluid will flow outwardly through passages 40 and saturate wicks 33. Preferably, passages 40 are more closely spaced near the distal end portion of the mandrel to provide proper fluid distribution upon the completely formed tube 41 passing from that end of the mandrel.

While wick 33 is shown as a solid elongated wick completely filling mandrel channel 32, it is apparent that radial passages 40 may communicate with longitudinal passages similar to those shown in Figures 2-4. In other words, the mandrel may be provided with a reduced channel portion similar to that shown at 22 (Figure 2) or the wick itself may be provided with longitudinal flow passages similar to passages 24 (Figure 3). Furthermore, longitudinal channel 32 may be equipped with a channel member, such as channel member 26 (Figure

4), the radial passages 40 being constructed and arranged to communicate with the longitudinal chamber of that member.

While we have disclosed several embodiments and variations of the present invention in considerable detail for purposes of illustration, it will be understood by those skilled in the art that many of these details may be varied without departing from the spirit and scope of this invention.

10. We claim:

1. In a tube winding machine having a stationary mandrel provided with at least one longitudinal groove along the outer periphery thereof, a resilient fluid absorbent wick mounted within said groove and having a curved outer surface flush with the curved peripheral surface of said mandrel, and fluid passage means including a bore extending longitudinally through said mandrel and communicating with said wick along substantially the entire length thereof for supplying tube coating fluid to said wick, whereby, upon operation of said tube winding machine said tube coating material is wiped from said wick upon the inner surface of a tube being wound upon said mandrel.

2. The structure of claim 1 in which said passage means including a plurality of radial passages extending between said bore and said wick, and a fluid reservoir equipped with a fluid flow conduit in communication with said bore for supplying tube coating fluid to said wick.

3. In a tube winding machine, a stationary cylindrical mandrel having a plurality of elongated peripheral channels extending substantially the entire length of said mandrel, a plurality of resilient fluid absorbent wicks mounted within said channels, said wicks having curved outer surfaces flush with the curved outer periphery of said mandrel, and fluid passage means including at least one longitudinal passage extending through substantially the entire length of said mandrel and communicating with said wicks for carrying tube coating fluid thereto, whereby, upon operation of said tube winding machine, said tube coating material is wiped from said wicks upon the inner surface of a tube being formed upon said mandrel.

4. The structure of claim 3 in which each of said wicks extends the length of one of said channels, said longitudinal passage comprising a longitudinal recess extending along the lower surface of each channel adjacent the bottom thereof for carrying and distributing tube coating fluid to said wick.

5. The structure of claim 3 in which an elongated channel member is mounted within each of the channels of said mandrel, said longitudinal passage comprising a longitudinally extending chamber provided by each channel member, said channel members each being adapted to receive tube coating fluid therein and having spaced openings along the top wall thereof, said wicks being carried by each of said channel members within the longitudinally extending chambers thereof and projecting upwardly through said openings for distributing fluid upon a tube being formed upon said mandrel.
